UNITED STATES PATENT OFFICE

171,289

DESK TRAY

William James Bargen, Waukegan, Ill.

Application March 24, 1953, Serial No. 24,188

Term of patent 14 years

(Cl. D74—5)

To all whom it may concern:

Be it known that I, William James Bargen, a citizen of the United States of America, residing at Waukegan, in the county of Lake and State of Illinois, have invented a new, original, and ornamental Design for a Desk Tray, of which the following is a specification, reference being had to the accompanying drawings, forming a part thereof.

In the drawings:

Figure 1 is a top plan view of a desk tray, showing my new design.

Figure 2 is an inner side elevational view of the same.

Figure 3 is an outer side elevational view of the same.

Figure 4 is a sectional view taken on the line 4—4 of Fig. 3.

Figure 5 is a front elevational view of the same.

Figure 6 is a rear elevational view of the same.

Figure 7 is a bottom plan view of the same.

I claim:

The ornamental design for a desk tray, as shown.

WILLIAM JAMES BARGEN.
